UNITED STATES PATENT OFFICE.

CLARENCE H. YOUNG, OF BOSTON, MASSACHUSETTS.

APPARATUS FOR HANDLING MATERIALS.

Application filed March 21, 1924. Serial No. 700,823.

This invention aims to provide improved apparatus for handling materials, primarily though not exclusively useful in drying operations.

5 In the drawings, which illustrate a preferred form of one embodiment of my invention:—

Figure 1 is a perspective view of the preferred form of material handling apparatus 10 showing a truck carrying a plurality of superimposed frames;

Fig. 2 is a perspective view of the bottom of one corner of a preferred form of a frame;

15 Fig. 3 is a perspective view of the parts shown in Fig. 2, as viewed from above the frame;

Fig. 4 is a section through the corners of two frames, showing their relation when 20 one frame is stacked upon the other; and

Fig. 5 is a section on the line 5—5 of Fig. 4, showing the relation of the foot on the upper frame to the top of the corner brace of the lower frame.

25 Referring to the drawings and to the preferred form of my invention selected for illustrative purposes, I have shown a number of frames piled one upon the other and spaced apart to provide between the frames 30 when stacked, spaces for the material and, for drying operations, to permit free circulation of air to the material on the frames. These frames are preferably, as illustrated, piled upon a truck or frame having rollers 35 thereon so that the whole apparatus may be moved about conveniently from place to place.

My invention is particularly useful as a 40 drying apparatus for drying gelatine, glue, shellac and the like, but is not limited to such use, as it may be used for a variety of other purposes.

The preferred form of frame illustrated 45 is not only very strong, because of a highly desirable corner brace construction, but is very sanitary, as is necessary for drying gelatine or other food stuffs, and is well adapted for stacking, and for transportation when stacked, each corner being held in 50 place relative to those underlying and overlying it, so that the frames cannot shift and upset during transportation by truck or otherwise.

55 The preferred form of frame illustrated includes four wooden side pieces joined together at the corners by lap or "halved"

joints, as best illustrated in Figs. 3 and 4, each lap or halved joint fitting closely. This type of joint is particularly sanitary because it presents a smooth unbroken surface at the 60 inside of the frame, as is best shown in Fig. 2. The outer corners of the wood are preferably sawn off to provide a flattened face, for purposes hereinafter more fully described. 65

A wire mesh is fastened to the side pieces and stretched across the intervening opening to support the substance to be dried, at the same time permitting a maximum amount of exposure of the substance to the air. 70

The corners illustrated are fastened together by bolts passing through corner brackets which hold the frame rigid, protect it, prevent separation of the joints and at the same time provide spacing means for spacing 75 stacked frames apart and preventing shifting of stacked frames relative to each other during transportation. The preferred form of corner bracket illustrated includes a top plate 2, a bottom plate 3 and a foot or 80 spacer 4.

The top plate 2 is formed of relatively thin sheet metal, generally rectangular and overlying a portion of each of the wooden pieces 5 and 6, but presenting ears laterally 85 engaging the wooden pieces. Two of these ears 7 and 8 are bent down against the inner surfaces of the wooden pieces 5 and 6, while a third ear 9 is bent down against or clenched against the flattened face 10 at the 90 outer corner of the wooden frame. Thus the ear 9 not only protects the exposed corner of the wooden frame, but exerts a substantial pressure opposed to the ears 7 and 8, thereby reinforcing and relieving the 95 holding bolts 11. Where, as is preferably the case, the ears, or some of them, are clenched by being hammered after assembly of the corner brackets with the frame, the wooden pieces are strongly urged toward 100 one another and a peculiarly strong and rigid joint is provided.

The bottom plate 3 may be identical with the top plate 2.

The preferred form of foot or spacer 4 105 presents a downwardly extending leg, preferably as illustrated U-shaped in cross-section, the bottom side of the U facing the inner corner of the frame, and may advantageously be held in place by the bolts 11, 110 11, engaging bosses 13, 14 exterior to the U-shaped leg and a web 15 interiorly of the

foot. The heads of the bolts 11 projecting above the top plate 2, constitute a preferred form of locating means for engagement with the foot of the superimposed corner, to prevent any slippage of the latter during transportation of the frames.

Thus, as illustrated in Figs. 4 and 5, the foot 4 rests upon the top plate of the frame below and the heads of the bolts 11 provide 10 suitable stops to prevent shifting of the frame above relative to the frame below, thereby preventing the drying frames from becoming upset when they are moved on their truck over rough floors and the like. 15 For some purposes, the bottom plate 3 and the foot 4 may be considered collectively to constitute a spacing means.

The type of corner construction described is particularly sanitary and the parts thereof are easily accessible for washing. The corners are strongly held together and there can be no opening of the joints because of the cooperation between the ears and the bolts. The ears 9, 9 also provide a protection for the corner of the wooden frame, thereby preventing damaging due to rough handling, accidental dropping or the like.

While I have shown and described one illustrative embodiment of a preferred form 30 of my invention, it will be understood that I have done so for purposes of clarification and not for purposes of limitation, and that various changes including alteration, omission, and particularly combinations of 35 individual parts may be made without departing from the scope of my invention, which is best described in the following claims.

Claims.

40 1. In drying apparatus, the combination of frames spaced apart by spacing members located at each corner of said frame and cooperating with triangularly arranged abutments located at each corner of said frames to prevent relative shifting of said frames.

2. A frame for drying apparatus including spacing members secured to one face of said frame adjacent the corners thereof and 50 a plurality of triangularly arranged stops located at the opposite face of said frame for cooperation with the spacing members of a similar frame, thereby to position said frame relative to a similar frame.

55 3. A sanitary frame for drying apparatus presenting a continuous unbroken face at the inside thereof, means for holding the corners of said frame together and for providing abutments for cooperation with spacing means provided on a similar frame to prevent shifting of one frame relative to the other.

4. A corner installation for a frame for use in drying apparatus including a spacing 60 member located at one side of a frame ad-

jaacent the corner thereof and means for securing said spacing member to the frame, said means presenting abutments at the opposite face of said frame from said spacing member for cooperation with a spacing member on a similar frame to prevent shifting of one frame relative to the other.

5. A sanitary frame for drying apparatus including frame members joined together at each corner by a plate, located at one face 75 of said frame, flanges extending from said plate over the edges of said frame, spacing means located at the other side of said frame presenting a foot and flanges extending over the sides of said frame, and securing means 80 holding said frame members, plate and spacing means together, said securing means presenting projecting means for engagement with a foot of a similar frame superimposed upon said frame.

85 6. A corner bracket for strengthening the corners of frames or the like, comprising, in combination, a top plate adapted to overlie a portion of two sides of the frame, ears extending from said plate and engaging the inner and outer faces of the frame, a bottom plate presenting a foot for spacing said frame away from an underlying frame, said bottom plate presenting ears for engagement with the outer and inner faces of said frame, and fastening means for securing said plates and frame together.

90 7. A fastening device for securing the corners of drying frames together including a top plate overlying a portion of two of 100 the sides of said frame, a plurality of ears extending from said plate over the edges of said sides, a bottom plate including a foot, a plurality of ears extending from said bottom plate to engage the edges of said sides, 105 a fastening bolt extending through said top plate, one side of said frame and said bottom plate, a bolt extending through said top plate, the other cooperating side of said frame and said bottom plate and a bolt extending through said top plate, both of said sides adjacent the corners thereof and said bottom plate, said bolts and ears holding said frame together to present a sanitary 110 inside corner for said frame thereby to exclude any of the material supported by said frame.

115 8. A corner installation for drying frames comprising a top plate and a bottom plate 120 presenting ears extending over a flat face provided at the extreme corner of the frame to reinforce and prevent damage to the frame and a plurality of bolts for securing said plates to the frame thereby to strengthen the corner thereof.

125 9. A frame for drying apparatus presenting at each corner thereof a sanitary halved joint, fastening and protecting means for said joint comprising plates having portions overlying the edges of said joint and spac-

- ing means extending from the corners of said frames, and held in place by said fastening means, for spacing said frame from a similar frame.
- 5 10. A frame for drying apparatus presenting at each corner thereof a U-shaped foot, and fastening means for holding said foot in place, said fastening means extending above the surface of said frame for locating engagement with a similar foot on a superimposed frame.
11. A corner bracket for a drying frame comprising, in combination, a clamping plate at each face of said frame adjacent the corners thereof, a U-shaped spacing member extending from one of said plates and attaching means for securing said plates and spacing member to said frame thereby to present means for spacing said frame
- 15 20 from a second frame and means for positioning a third frame relative to said first-mentioned frame.
12. A drying frame including a corner bracket presenting a U-shaped spacing member at each corner thereof, and attaching means for securing said brackets to said frame, said attaching means at each corner cooperating with attaching means at each of the other corners to position a second frame relative thereto.
- 25 30 13. A corner brace assembly comprising opposed plates, each presenting portions extending at right angles to each other in the same plane for overlying intersecting frame sides, and each presenting a plurality of ears closely embracing the inner faces of the frame sides and the outer face of the frame.
14. A corner brace assembly comprising opposed plates, each presenting portions extending at right angles to each other in the same plane for overlying intersecting frame sides, and each presenting a plurality of ears closely embracing the inner faces of the frame sides and each presenting an outer ear opposed to said first-named ears and overlying, protecting and closely embracing the extreme corner of the frame.
15. A sanitary frame for drying apparatus presenting a continuous unbroken face at the inside thereof, means for holding the corners of said frame together and for providing abutments for cooperation with spacing means provided on a similar frame to prevent shifting of one frame relative to the other, and spacing elements secured to the corners of said frame by said means for spacing said frame from a similar frame.

In testimony whereof, I have signed my name to this specification.

CLARENCE. H. YOUNG.
